P.J. Hickey

WITNESS:

Thomas Thomas,
INVENTOR
BY Victor J. Evans
ATTORNEY

UNITED STATES PATENT OFFICE.

THOMAS THOMAS, OF SCRANTON, PENNSYLVANIA.

SAFETY DEVICE FOR TANKS.

Application filed June 17, 1925. Serial No. 37,806.

To all whom it may concern:

Be it known that I, THOMAS THOMAS, a citizen of the United States, residing at Scranton, in the county of Lackawanna and 5 State of Pennsylvania, have invented new and useful Improvements in Safety Devices for Tanks, of which the following is a specification.

The object is the provision of a fire proof 10 filter for tanks containing explosive liquids which is characterized by simplicity in its construction and reliability and efficiency in practical use.

To the attainment of the foregoing the invention consists in the improvement as hereinafter described and definitely claimed.

In the drawings:

Figure 1 is an approximately central vertical longitudinal sectional view through the 20 filter in applied position.

Figure 2 is a sectional view on the line 2—2 of Figure 1.

Figure 3 is a sectional view on the line 3—3 of Figure 1.

In Figure 1 of the drawings a gasoline or other explosive liquid tank is indicated by the numeral 1. The tank is provided with the usual filler opening that is surrounded by outwardly directed interiorly 25 threaded flange 2. Screwed in the flange 2 there is the threaded portion 3 of a flanged collar 4 providing an element of the improvement. The shoulder of the collar rests on the flange 2. The collar has secured to 30 its bore, or if desired formed therewith, a tubular member 5. The member 5 has its lower open end flanged inwardly, as at 6. Resting on this flange there is the lower perforated disc or plate 7 of a receptacle 8 for 35 a filtering medium 9. The top of the receptacle 8 is also perforated, as at 10.

The collar 4, at its juncture with its sleeve extension 4, is formed with an inwardly directed shoulder 11. This shoulder is normally contacted by one end of a cylindrical 45 member 12. The member 12 has both of its ends reduced to form shoulders on which rest closely woven mesh plates 13. The inner end of the sleeve 12 has secured thereto 50 a transverse plate 14 provided with a boss

15. Surrounding the boss is one end of a helical spring 16, the opposite end of which resting on the top of the receptacle 8.

The usual closure cap 17 is screwed in the 55 sleeve 4.

When gasoline or like fluid is poured into the tank 1 the nozzle end will rest on the upper screen of the slidable member 12. The gasoline will flow through both of the 60 screens of the said member and through the filtering medium in the receptacle 8. Of course, the weight of the gasoline and the weight of the nozzle resting on the slidable member 12 will force the same in the tube to 65 approximately the dotted line position in Figure 1. The fluid entering the tank is thoroughly filtered. Should the vapor explode on the outside of the tank the fire excluding screens 13 in the member 12 will 70 prevent fire entering the said tank. As soon as the pressure of the delivery nozzle is relieved therefrom the member 12 will be influenced by the spring 16 to initial position.

While I have illustrated a satisfactory embodiment of my improved device my features of invention are capable of extended application and I do not wish to be limited to the specific structure shown and described.

Having described the invention, I claim:

1. In combination with the supply tank 80 for gasoline or other explosive liquids, of a safety filtering spout therefor, including a tubular member removably secured in the filler opening of the tank, an apertured receptacle for a filtering medium at the bottom 85 of the tube, a hollow slidable member at the top of the tube having closely woven wire mesh at the ends thereof, spring means influencing the last mentioned member in an upward direction in the sleeve and a removable closure for the tube.

2. In a device for the purpose set forth, and the combination with a supply tank for gasoline or other explosive liquids, comprising a threaded sleeve screwed in the inlet of the supply tank and having a tube extending therefrom and the said tube having its outer end flanged inwardly, said sleeve having a shoulder with which the opposite end of the tube contacts, an apertured receptacle rest- 100

ing on the lower flange of the tube and having arranged therein a filtering medium, a tubular slidable member in the sleeve having its ends depressed to provide seats, closely woven wire discs secured on the seats, a boss carrying plate secured centrally on the inner end of the slidable member, and a com-

paratively light helical spring surrounding the boss, received in the tube and contacting the top of the apertured receptacle, in combination with a closure for the sleeve. 10

In testimony whereof I affix my signature.

THOMAS THOMAS.
